UNITED STATES PATENT OFFICE.

OSCAR V. PAYNE, OF CLEVELAND, OHIO, ASSIGNOR TO AUTO-ORDNANCE CORPORATION, OF NEW YORK, N. Y., A CORPORATION OF NEW YORK.

MAGAZINE FOR FIREARMS.

1,361,402.

Specification of Letters Patent. Patented Dec. 7, 1920.

Application filed July 27, 1920. Serial No. 399,284.

To all whom it may concern:

Be it known that I, OSCAR V. PAYNE, a citizen of the United States of America, and resident of Cleveland, in the county of Cuyahoga and State of Ohio, have invented new and useful Improvements in Magazines for Firearms, of which the following is a specification.

This invention relates to an improved magazine for firearms and more particularly to a magazine of the drum type, the present invention being in the nature of an improvement on my prior form of drum magazine as disclosed in my Patent No. 1,347,755, granted July 27, 1920.

Magazines of this type are particularly adapted for use with machine guns or other firearms firing sustained bursts with great rapidity of fire. The magazines are required in large numbers and therefore simplicity and relative low cost of manufacture are essential. It is highly important that the device be compact and contain as few parts as possible and that these parts be of rugged construction and positive in operation since any jam or failure to function properly may have very serious results.

Broadly defined my magazine comprises a flat drum having spiral guideways adapted to guide cartridges to an opening in the periphery and having a rotor adapted to force the cartridges along the guideway.

It is an object of the present invention to simplify the construction, assembly and operation of rotary magazines of the character described. It is an object to provide a rotor for such a magazine which is composed of simple stamping joined by integral connecting elements with consequent economy in manufacture and reduction in the number of parts. It is also an object to provide positive cartridge guide or deflecting means adjacent the cartridge delivery opening. Other and further objects will appear as the description proceeds.

I have illustrated a preferred embodiment of my invention in the accompanying drawings in which—

Figure 1 is a plan view of the magazine with the cover removed;

Fig. 2 is a section taken on line 2—2 of Fig. 1;

Fig. 3 is a fragmentary perspective view showing a portion of the rotor.

Fig. 4 is a fragmentary section showing the spring connection;

Fig. 5 is a fragmentary plan view showing the spring detent device and the body clip catch;

Fig. 6 is a section on line 6—6 of Fig. 5;

Fig. 7 is a fragmentary section showing the cover catch; and

Fig. 8 is a section on line 8—8 of Fig. 7.

The magazine comprises the sheet metal body member 9, having the upturned edge 10, the member being centrally perforated and having the inturned bearing 11 surrounding the central perforation. The cover member 12 has the peripheral flange 13 adapted to make a close fit upon the outer face of the upturned edge 10 of the body member 9. The cover is centrally perforated and the perforation is surrounded by the inturned bearing flange 14. The body member 9 has its periphery cut away upon a curve at 15 and the adjacent portion of the upturned edge 10 is also cut away and turned back upon itself at 16. The cover is similarly cut away at 17 but for a greater depth.

The body member contains the spiral guideway 18 which may be attached thereto in any desired manner as by welding. The rear end of the guideway is reversed upon itself at 19 to prevent the insertion of cartridges in that portion. A similar guideway 20 formed of somewhat thicker material is fastened to the inner side of the cover member 12.

The hollow shaft 21 passes through the two members 9 and 12 and bears upon the flanges 11 and 14. The end of the shaft 21 which projects outward through the magazine body member 9 is externally grooved to receive the body clip or catch 22. This clip 22 is shown in Fig. 5 and comprises a forked portion engaging the shaft and an extended arm 23 having an inturned edge 24 fitting into a slot in the body. The clip possesses sufficient resiliency to maintain the inturned edge engaged in the body.

The opposite end of the shaft projects outwardly through the cover 12 and is externally grooved to receive the cover catch 25. This catch is pivoted to the cover at 5 26 and the opposite end is indented to form the catch 27 which coacts with a similar indentation 28 in the cover as shown in Fig. 8.

The rotor 29 is preferably formed of a 10 single stamping of sheet metal centrally perforated and having the inturned flange 30 adapted to bear on the shaft 21. The rotor is provided with a plurality of outwardly extending feet 31. The front of 15 each foot as shown is substantially upon a radial line, while the rear of the foot inclines away from the front upon such an angle that the distance between the front of one foot and the rear of the adjacent foot 20 remains substantially constant as the distance from the center increases. The front and rear surfaces of the feet which will contact with the cartridges in the magazine are provided with the axially extending flanges 25 32 and 33, which are formed integrally of the sheet metal of the rotor. The rear surface is formed upon two successive intersecting flat curves as shown in the drawings in order to better contact with and retain the 30 cartridges in the channels. The outer surfaces of the feet are cut away at 34 to permit the introduction of an additional cartridge in the space occupied by each foot.

As best shown in Fig. 2, the rotor is dished 35 in stamping so that while the flat central portion is adjacent the cover member the feet are spaced midway between the body and cover and substantially fill the distance between the two guides 18 and 19.

40 Adjacent the far side of the opening between the lips 16, are the two cartridge deflectors or guide members 35 which are riveted to the upturned edge 10 of the body member 9. The faces 36 of these deflectors 45 adjacent the opening are curved concavely so as to urge the cartridge up against the opening between the lips 16.

The cup shaped spring casing 37 has the bearing flange 38 resting upon the shaft 21. 50 The edge of the cup is provided with lugs 39 which pass into openings in the rotor and are upset to retain the cup and rotor together. The clock spring 40 is contained within the casing 37, its outer end being 55 attached to the cup and its inner end to the shaft 21 in the manner shown in Figs. 2 and 4. The collar 41 is slipped on to the shaft 21 and the pin 42 is passed through registering openings in collar and shaft, the 60 head of the pin being countersunk into the collar. The upper end of the pin extends through the collar and through a perforation adjacent the end of the spring. The re-

65 tainer 43 is then sprung around the first turn of the spring, an opening receiving the upper end of the pin and the opposite end of the retainer covering the head of the pin 42.

60 The portion of the shaft 21 adjacent the inner side of the body of the magazine is provided with the integral flange 44 to 70 which is bolted the ratchet disk 45. The outer periphery of this disk is formed into a plurality of substantially tangential spring fingers 46 the ends of which are bent downward to contact with the magazine 75 body 9. This magazine body has pressed into it a plurality of detents 47 adapted to coact with the ends of these fingers.

80 In the use of the magazine the cover 12 is removed by lifting outward the free end of the cover catch 25 until the catch 27 is disengaged and then swinging the member 25 counter clockwise about its pivot 26 until the shaft 21 is disengaged. The cover 12 may then be lifted off.

85 The magazine is now filled by placing rows of cartridges base down between the guides 18 in the spaces between the feet 31, cartridges also being placed in the cut out 90 portions 34 of the feet.

90 The cover may then be replaced and locked by means of the catch 25. The bullets are of less diameter than the base portions of the cartridges and will lie between the guides 19, which due to their greater 95 thickness have a closer spacing than the guides 18.

With the magazine filled and closed a handle is inserted in the bore of the shaft 21 as indicated in Fig. 2. The inner end 100 of the handle is bifurcated to engage the pin 42. The handle is rotated in a counter clockwise direction as seen from the rear of Fig. 2, or in Fig. 5, the fingers 46 slipping past the detents 47 during the winding 105 but retaining the spring against unwinding by their engagement with these detents when winding is stopped.

110 The tendency of the rotor 29 to be rotated by this winding of the spring is prevented by the engagement of the first cartridge 115 with the cartridge guides or deflectors 35 and lips 16. The opening between the lips 16 is less than the diameter of a cartridge so that the cartridge cannot be forced upward and out by the pressure of the rotor.

120 In fitting the magazine to a gun the cover side of the magazine is placed toward the muzzle. The first cartridge projects partly out of the magazine opening between the lips 16, and the gun bolt extending down through the cut away portion 15 of the magazine body will contact with the base 125 of the cartridge and will carry it forward through the opening 17 in the magazine cover and thus out of the magazine and into

the barrel of the gun. It should be noted that the opening 17 is deeper than the aligned opening 15.

5 The force of the spring 40 carries the rotor around and positions the cartridges successively between the lips 16. The spring is made of such strength to cause the rotation to be of sufficient rapidity to insure the presentation of a cartridge for every movement of the gun bolt. The engagement of the cartridge with the guides 35 and lips 16 automatically stops the rotor at the proper point between shots.

10 While the guides 18 and 20 have been referred to as spiral, they are preferably not formed upon a true logarithmic spiral but are formed by two eccentric circular arcs as shown in the drawing in order to minimize lost space due to the attenuated end of 15 the spiral.

15 An important feature of the invention lies in the broad bearing flanges which both body and rotor have upon the shaft. These broad bearings greatly facilitate the action 20 of the magazine. When winding the spring, the shaft rotates upon both sets of bearings and when the magazine is feeding cartridges to a gun, the shaft is stationary and the rotor revolves thereon upon the bearings 25 30 and 38.

30 I claim:

35 1. In a drum magazine, a rotor comprising a unitary sheet metal member having integral cartridge carrying feet extending therefrom.

40 2. In a drum magazine, a rotor comprising a unitary sheet metal member having integral cartridge carrying feet extending therefrom, the feet having axially extending flanges upon each side.

45 3. In a drum magazine, a rotor comprising a unitary sheet metal member having integral cartridge carrying feet extending therefrom, the feet increasing in width as they extend outward, whereby the distance beyond adjacent feet is substantially constant.

50 4. In a drum magazine, a rotor comprising a unitary sheet metal member having integral cartridge carrying feet extending therefrom, and an indentation in the outer edge of each foot adapted to receive a cartridge.

55 5. In a drum magazine, a rotor comprising a unitary sheet metal member having a central perforation surrounded by an integral inturned bearing flange.

60 6. In a drum magazine, a rotor comprising a unitary sheet metal member having integral cartridge carrying feet extending therefrom, the feet extending in a plane substantially parallel to that of the body of the rotor but offset therefrom.

65 7. A drum magazine comprising a body

member, a cover, a shaft extending therebetween and a rotor adapted to rotate upon said shaft, integral inturned flanges being formed upon the cover and body member to serve as bearings for the shaft.

70 8. A drum magazine comprising a body member, a cover, and a rotor, spiral guides upon the cover and body members, the guides being adapted to receive the ends of cartridges, the width of the guideway adapted to receive the bullet end of the cartridges being less than the width of the guideway adapted to receive the cartridge bases.

75 9. A drum magazine comprising a body member, a cover, and a rotor, spiral guides upon the cover and body members, the guides being adapted to receive the ends of cartridges, the thickness of one of said guides being less than that of the other guides whereby the width of the guideway adapted to receive the bullet end of the cartridges is less than the width of the guideway adapted to receive the cartridge bases.

80 10. A drum magazine comprising a body member, a cover, a shaft therebetween and a rotor journaled on said shaft, a spring housing cup journaled on said shaft, its edge being attached to the rotor and a spring located in said spring housing, the rotor and housing having integral inturned flanges serving as bearings on the shaft.

85 11. A drum magazine comprising a body member, a cover, a shaft therebetween and a rotor journaled on said shaft, a spring having a cup journaled on said shaft, its edge being attached to the rotor and a spring located in said spring housing, the rotor and housing having integral inturned flanges serving as bearings on the shaft, and the cover and body members having inturned flanges serving as bearings for the shaft.

90 12. A drum magazine comprising a body member, a cover, a shaft therebetween and a rotor journaled on said shaft, a spring housing cup journaled on said shaft, its edge being attached to the rotor and a spring located in said spring housing and adapted to rotate the rotor, and ratchet means attached to the shaft and coating with body member to prevent rotation of the shaft in one direction.

95 13. A drum magazine comprising a body member, a cover, a shaft therebetween and a rotor journaled on said shaft, and a spring adapted to rotate the rotor, a pin passing through the shaft, the inner end of the spring having a perforation fitting over one end of the pin, and a spring retainer adapted to fit about the inner portion of the spring and having a perforation adapted to receive the end of the pin.

100 14. A drum magazine comprising a body

member, a cover, a shaft therebetween and a rotor journaled on said shaft, and a spring adapted to rotate the rotor, a pin passing through the shaft, the inner end 5 of the spring having a perforation fitting over one end of the pin, the shaft being hollow whereby a winding handle may be inserted therein to grip the pin and thus rotate the shaft and wind the spring.

15. In a drum magazine, spiral cartridge 10 guideways, means urging cartridges along said guideways, a peripheral opening in the magazine of less width than a cartridge, and fixed deflectors urging cartridges from the guideway against the opening. 15

Signed by me at Cleveland, Ohio, this twenty-first day of July, 1920.

OSCAR V. PAYNE.
